Primary Examiner — Joseph Kukella*Assistant Examiner* — Heather Ann Laaveg-Wencl(74) *Attorney, Agent, or Firm* — Paratus Law Group, PLLC(57) **CLAIM**The ornamental design for a LOCKING DEVICE FOR BAG
ACCESSORIES as shown and described.

DESCRIPTION

FIG. 1 is a front, top, and left perspective view of a LOCK-
ING DEVICE FOR BAG ACCESSORIES, showing the
claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, top, and left perspective view thereof,
showing a state in which fastening parts thereof are
fastened;FIG. 9 is a cross-sectional view taken along line 9-9 shown
in FIG. 2; andFIG. 10 is a reference view showing the claimed design in
use.The long dash short dash broken lines and arrows shown in
FIG. 2 are used to identify the cross-sectional view and the
short evenly spaced broken lines shown in FIG. 10 depict
environment. The broken lines form no part of the claimed
design.**1 Claim, 5 Drawing Sheets**(56)
